WIRE TIGHTENING AND TWISTING
MECHANISMHenry Wilfred Cox, North Melbourne,
Victoria, AustraliaApplication June 22, 1935, Serial No. 27,986
In Australia June 29, 1934

9 Claims. (Cl. 140—93)

This invention relates to improved means for tightening and twisting a wire about a case or package and includes means whereby rotation of a single driving shaft is adapted to effect automatic and independent tightening to a predetermined degree of the wire about the case or package and twisting of the strands of the tightened wire about each other.

I provide two independent shafts to be driven, one shaft constituting portion of a capstan assembly to effect tightening of the wire and the other to effect twisting of the strands and cutting of the excess lengths of the wire. Between the driving shaft and the said driven shafts is positioned a gear train comprising a sun-wheel keyed to the driving shaft, a planet wheel in mesh with the sun wheel, and a spur gear in mesh with the planet wheel and in mesh with a spur wheel loose on the driving shaft. By means of intermediate gearing independent rotation of each of the driven shafts in turn is automatically obtained to effect orderly sequence of operations of the machine.

In the accompanying drawing which illustrates one form of the invention:

Fig. 1 is a part sectional side elevation of the mechanism;

Fig. 2 is a plan of the same;

Fig. 3 is a transverse sectional elevation on line 3—3 of Fig. 1 and indicating portion of the gear on the other side of the section;

Fig. 4 is a similar view on the line 4—4 of Fig. 1;

Fig. 5 is a similar view on the line 5—5 of Fig. 1.

A driving shaft 10, mounted in bearings 11, 11 and adapted to be manually or power operated, is fitted with a sun gear wheel 12 which meshes with a planet wheel 13. Planet gear 13 meshes with a spur gear 14 which in turn meshes with a spur wheel 15 loose on shaft 10. Gear 15 is integral with a gear wheel 16 and with a holding plate 17.

The plate 17 is provided with an angularly faced slot into which is fitted a similarly shaped withdrawable locking pin 18 which in its housed position in the plate prevents rotation of the gears 15 and 16.

A framing 19 positioned about the shaft 10 and carrying the gears 13 and 14 encases the gears 12, 13, and 14 and is integral with a sleeve 20 which is loose on shaft 10. Sleeve 20 is fitted with a one-way clutch 21 and is secured to a bevel gear which meshes with the crown wheel 22 of a wire tightening capstan assembly 23. The

details of construction and of operation of this assembly are fully described in my United States Patent 1,956,234.

An idler gear 24 meshes with gear 16 and also with a gear 25 fast on a shaft 26 which shaft is one of the driven shafts mentioned above. Gear 25 meshes with a wire twisting pinion 27. On shaft 26 are locked adjustable cams 28, 29 which are adapted to operate cam shaped wire cutters 30 and 31 respectively, cutter 31 being adapted to nick but not sever the wire leading to the assembly 23.

Assuming that pin 18 is in housed position in plate 17, rotation of shaft 10 effects rotation of gears 13 and 14. Since gears 15 and 16 are locked by the pin 18 the gears 13 and 14 and the framing 19 revolve about the gear 15 with the result that the sleeve 20 and gear 22 effect rotation of the wire tightening assembly 23, the shaft 26 remaining stationary.

Should pin 18 be withdrawn from plate 17 and the assembly 23 be under tension due to a wire tightened by the capstan, rotation of shaft 10 effects rotation of gears 15, 16, 24, 25, and 27 and of shaft 26, the capstan assembly 23 remaining stationary.

The driven capstan of the wire tightening means and the driven shaft of the wire twisting and cutting means are thus operated independently by the driving shaft in such a manner that while either one of these driven members is being rotated the other is stationary.

The ratio of the gears 25 and 27 to each other is selected so that gear 27 makes three complete revolutions for each complete rotation of gear 25.

Locking pin 18 is connected by a link 32 with a swingable wire gripping assembly 33 the construction and operation of which is fully set out in my above mentioned United States patent.

Assuming that a wire to be tightened about a case or package and twisted has been positioned and held by the assembly 23 and by the assembly 33, the effective tensioning of the wire by means of the assembly 23 partially rotates the assembly 33 in counter-clockwise direction against the resistance of spring 34, thus withdrawing pin 18 from plate 17. A spring pressed catch 35 then snaps in position behind the head 36 of assembly 33 and retains the pin in non-locking position and permitting the gears 16 and 25 and shaft 26 to be rotated by the driving shaft 10.

Cam 28 is positioned on shaft 26 to effect early operation of wire cutter 30 to sever the wire leading to assembly 33, this does not af-

fect the rotation of the twisting pinion 27 since the head 36 is held by the catch 35. Shaft 26 continues to rotate, wire cutter 31 nicks its associated wire leading to assembly 23, and the twisting pinion continues its series of rotations until a trip cam 37 on the shaft 26 removes the catch 35 from its retaining position behind the head 36.

Pin 18 is then at once returned to locking position in the plate 17 by means of springs 38 on a slideable frame 39 which carries the pin, and further rotation of shaft 10 increases the tension on the nicked wire on the capstan assembly side until the wire is snapped. The return of pin 18 prevents over-winding of the twisted wires.

I claim:—

1. Wire tightening and twisting mechanism comprising a drive-shaft, a sun-wheel fast to said shaft, a planet-wheel in mesh with said sun-wheel, a spur-gear in mesh with said planet-wheel, a gear-wheel loose on said shaft in mesh with said spur-gear, a withdrawable locking-pin adapted to prevent and to permit rotation of said loose gear-wheel, a rotatable framing carrying said spur-gear, and a wire-tightening capstan in mesh with said framing, said locking-pin being withdrawable by a wire tightened by said capstan.

2. Wire tightening and twisting mechanism comprising a drive-shaft, a sun-wheel fast to said shaft, a planet-wheel in mesh with said sun-wheel, a spur-gear in mesh with said planet-wheel, a gear-wheel loose on said shaft in mesh with said spur-gear, a withdrawable locking-pin adapted to prevent and to permit rotation of said loose gear-wheel, means for withdrawing said locking-pin, an idler-gear in mesh with said loose gear-wheel, a rotatable shaft, a gear-wheel fast thereon in mesh with said idler-gear, and adjustable cam-shaped wire-cutters on said rotatable shaft.

3. Wire tightening and twisting mechanism comprising a drive-shaft, a sun-wheel fast to said shaft, a planet-wheel in mesh with said sun-wheel, a spur-gear in mesh with said planet-wheel, a gear-wheel loose on said shaft in mesh with said spur-gear, a withdrawable locking-pin adapted to prevent and to permit rotation of said loose gear-wheel, means for withdrawing said pin, an idler-gear in mesh with said loose gear-wheel, a rotatable shaft, a gear-wheel fast thereon in mesh with said idler-gear, and a wire-twisting pinion in mesh with said last-mentioned gear-wheel.

4. Wire tightening and twisting mechanism comprising a drive-shaft, a sun-wheel fast to said shaft, a planet-wheel in mesh with said sun-wheel, a spur-gear in mesh with said planet-wheel, a gear-wheel loose on said shaft in mesh with said spur-gear, a rotatable framing carrying said spur-gear, a wire-tightening capstan in mesh with said framing, a withdrawable locking-pin adapted to prevent and to permit rotation of said loose gear-wheel on said drive-shaft, said pin being adapted to be withdrawn by a wire tightened by said capstan, and a spring-pressed catch adapted to retain said locking-pin in withdrawn position.

5. Wire tightening and twisting mechanism

comprising a drive-shaft, a sun-wheel fast to said shaft, a planet-wheel in mesh with said sun-wheel, a spur-gear in mesh with said planet-wheel, a gear-wheel loose on said shaft in mesh with said spur-gear, a rotatable shaft, adjustable cam-shaped wire-cutters on said rotatable shaft, a gear-train in mesh with said rotatable shaft and said drive-shaft, a withdrawable locking-pin adapted to prevent and to permit rotation of said loose gear-wheel, means for withdrawing said locking-pin, a spring-pressed catch to retain said pin in withdrawn position, a trip-cam on said rotatable shaft adapted to release said catch, a wire-twisting pinion in mesh with said gear-train, and a spring-urged slideable frame adapted to return said locking-pin to locking position.

6. Wire tightening and twisting mechanism comprising a drive-shaft, a sun-wheel fast to said shaft, a gear loose on said shaft, a gear-train between said sun-wheel and gear, a locking-pin adapted to prevent and to permit rotation of said loose gear, means for withdrawing said pin, a rotatable shaft driven by said loose gear, and wire-cutters on said rotatable shaft.

7. Wire tightening and twisting mechanism comprising a drive-shaft, a sun-wheel fast to said shaft, a gear loose on said shaft, a gear-train between said sun-wheel and gear, a locking-pin adapted to prevent and to permit rotation of said loose gear, means for withdrawing said pin, a rotatable shaft driven by said gear, wire-cutters on said rotatable shaft, a gear-train between said rotatable shaft and drive-shaft, a spring-pressed catch retaining said pin in withdrawn position, a trip member to release said catch, a wire-twisting pinion in mesh with said gear-train, and a spring-urged slideable frame adapted to return said locking-pin to locking position.

8. Wire tightening and twisting mechanism comprising a drive-shaft, a wire-tightening assembly, a wire-twisting pinion, drive-trains driven by said shaft for actuating said assembly and pinion, said assembly and pinion trains being initially operative and inoperative respectively, means actuated by tension of a wire operated on whereby said assembly and pinion trains are simultaneously rendered inoperative and operative respectively, a catch whereby said trains are retained in the latter state, mechanism whereby said catch is released on completion of the twisting operation, and a spring restoring said trains to their initial state.

9. Wire tightening and twisting mechanism comprising a drive-shaft, a wire-tightening assembly, a wire-twisting pinion, drive-trains driven by said shaft for actuating said assembly and pinion, said assembly and pinion trains being initially operative and inoperative respectively, means actuated by tension of a wire operated on whereby said assembly and pinion trains are simultaneously rendered inoperative and operative respectively, a wire-cutter actuated by said pinion drive-train, a catch whereby said trains are retained in the latter state, mechanism whereby said catch is released on completion of the twisting operation, and a spring restoring said trains to their initial state.

HENRY WILFRED COX.
